UNITED STATES PATENT OFFICE.

HENRY M. LYITLE, OF BRADDOCK, PENNSYLVANIA.

DOUBLE-DECKED FREIGHT-CAR.

SPECIFICATION forming part of Letters Patent No. 735,123, dated August 4, 1903.

Application filed September 12, 1902. Serial No. 123,094. (No model.)

To all whom it may concern:

Be it known that I, HENRY M. LYITLE, a citizen of the United States, residing at Brad-
dock, in the county of Allegheny and State of
Pennsylvania, have invented a new and use-
ful Improvement in Double-Decked Freight-
Cars, of which improvement the following is
a specification.

This invention relates to an improved
10 freight railway-car, and more particularly to
that class of cars known as "double-decker"
used for the transportation of hogs, sheep,
calves, and other like animals, the object be-
ing to provide a means whereby the upper
15 deck or floor may be elevated to a position
beneath the roof of the car, converting the
same into an ordinary freight or cattle car;
and with these and other objects in view my
invention consists in the certain details of
20 construction and combination of parts, as will
be fully described hereinafter.

In the accompanying drawings, Figure 1 is
an end sectional elevation of my improved
25 freight-car, a part of which is shown in out-
side elevation, the said view being construct-
ed and arranged in accordance with my in-
vention. Fig. 2 is a sectional plan view of
one end of the car. Fig. 3 is a side central
30 elevation of the car, showing the altered po-
sition of the upper floor in dotted lines.

To construct a freight-car in accordance
with my invention, the said car consisting of
the body portion 1, formed in a manner well
known in the art, I arrange beneath the roof
35 a shaft 3, mounted in suitable bearings 4 and
extending in the direction of the length of the
said car, the ends of the said shaft projecting
beyond the car a short distance. Each end
of the above-mentioned shaft 3 is fitted with
40 a ratchet-wheel 6 and is also provided with a
rectangular portion 5 for the purpose of con-
necting hand wrenches or cranks 9 thereto.

Arranged within the body of the car 1 and
occupying almost the entire width and length
45 of the car is a platform or upper deck 10, con-
structed of suitable material and supported
by stringers 18, cross-pieces 16, and truss-
bolts 17 in a manner that when the said deck
50 is at rest or the position shown on the draw-
ings the weight of the same, together with its
load, will be supported by timbers or fixed
pieces 15, attached firmly to each inner side

of the car. Mounted in bearings at each of
the angles of the car and beneath the roof 2
are four shives 8, over which chains 12 are 55
passed, one end of each being connected by
14 to each angle of the upper deck 10 and the
other extremities attached to drums 7, rigidly
placed on the shaft 3, one at either end of the
car. Placed at one side of each of the ratchet- 60
wheels 6 are pawls 11, the purpose of which
is to prevent the shaft 3 from turning in one
direction unless the said pawl is released.

In operation the upper deck 10 will occupy
the position shown on the drawings when the 65
car is used for shipping hogs, sheep, calves,
and other small animals, and when it is de-
sired to use the said car for ordinary freight
purposes the upper deck 10 is elevated to the
position shown in dotted lines at Fig. 3 of the 70
drawings.

To accomplish the above-mentioned move-
ment of the upper deck 10, it is only neces-
sary to operate the cranks 9 at either end of
the car in the proper direction. The pawl 11 75
and ratchet-wheel 6, together with the con-
necting-chains 12, will elevate and retain the
said deck at any desired elevation.

It is a well-known fact that these double-
decked cars such as are now in common use 80
cannot be used for any other purpose than of
transporting small animals, and as the upper
deck is permanent or made rigid with the
body of the car it is impossible to use the lat-
ter for any other purpose than that for which 85
it was built.

It is obvious that various slight modifi-
cations and changes may be made in the details
of construction without departing from the
spirit of the invention. 90

Having thus described my invention, what
I claim, and desire to secure by Letters Pat-
ent, is—

The combination with the car-body, fixed
beams secured to the sides and extending 95
throughout the length of the car, a deck slid-
ably mounted in the car and adapted to seat
on said beams, cross-beams secured to the
under face of the deck and adapted to rest on
said fixed beams, truss-bolts engaging the 100
under faces of said deck-beams and being at-
tached to the end of the deck, stringers for
said deck, a shaft journaled beneath the roof
of the car, said shaft projecting from both

2
ends of the car and provided with rectangular portions for attaching means for rotating the same, ratchet-wheels carried by the projecting portions of the shaft, means for locking said shaft against rotation, said means adapted to engage the ratchet-wheels, pulleys mounted in the upper corners of the car-body, angle-irons secured to the corners of the said deck provided with eyes, chains passing over 5 the said pulleys, one end thereof connected

to the said eyes and the other end secured to the said shaft, substantially as described.

In testimony whereof I have hereunto signed my name in the presence of two subscribing witnesses.

HENRY M. LYTHE.

In presence of—

M. E. HARRISON,
M. HUNTER.
